(57) **CLAIM**

The ornamental design for a combined card and fingerprint reader, as shown and described.

DESCRIPTION

FIG. 1 is a perspective view of a first embodiment of a combined card reader and fingerprint reader;

FIG. 2 is front view of the combined card and fingerprint reader of FIG. 1;

FIG. 3 is a back view of the combined card and fingerprint reader of FIG. 1;

FIG. 4 is a right side view of the combined card and fingerprint reader of FIG. 1;

FIG. 5 is a left side view of the combined card and fingerprint reader of FIG. 1;

FIG. 6 is a top view of the combined card and fingerprint reader of FIG. 1;

FIG. 7 is a bottom view of the combined card and fingerprint reader of FIG. 1;

FIG. 8 is a perspective view of a second embodiment of the combined card and fingerprint reader;

FIG. 9 is front view of the combined card and fingerprint reader of FIG. 8;

FIG. 10 is a back view of the combined card and fingerprint reader of FIG. 8;

FIG. 11 is a right side view of the combined card and fingerprint reader of FIG. 8;

FIG. 12 is a left side view of the combined card and fingerprint reader of FIG. 8;

FIG. 13 is a top view of the combined card and fingerprint reader of FIG. 8; and,

FIG. 14 is a bottom view of the combined card and fingerprint reader of FIG. 8.

The broken lines in the drawing indicate environmental structure and form no part of the design to be patented.

1 Claim, 8 Drawing Sheets
